UNITED STATES PATENT OFFICE.

GEORGE BARTLETT, OF BOSTON, MASSACHUSETTS, ASSIGNOR TO HIMSELF
AND ARTHUR W. EATON, OF SAME PLACE.

PHOTOGRAPH AND AUTOGRAPH ALBUM.

SPECIFICATION forming part of Letters Patent No. 257,203, dated May 2, 1882.

Application filed August 1, 1881. (No model.)

To all whom it may concern:

Be it known that I, GEORGE BARTLETT, of Boston, of the county of Suffolk and State of Massachusetts, have invented a new and useful

5 Improvement in the Manufacture of Photograph and Autograph Albums; and I do hereby declare the same to be described in the following specification and represented in the accompanying drawings, of which—

10 Figure 1 is a front view, and Fig. 2 an edge or bottom view, and Fig. 3 a longitudinal section of one sheet of an album of my improved kind. Fig. 4 is an edge view of three connected leaves of the album, the book being composed 15 of any proper number of them.

The album as made in accordance with my invention is intended to be both for photographs and autographs, it having to each sheet not only two pockets for holding photographs, but 20 two bordered spaces for receiving writing or autographs.

Each photograph-pocket has its mouth at the lower edge of the sheet, one pocket being arranged near one end of the sheet and the other near the other end of the sheet, the bordered space for the autograph being between the pocket and the other end of the sheet, all being as represented in Figs. 1 and 2, in which the sheet shown at A has two photograph-pockets, a b, whose mouths are indicated at c and d, and picture-openings at e and f, the bordered autograph-receiving spaces being shown at g and h, each of which has its border i. Thus it will be seen that when photographs are within 35 the pockets one of such photographs will be seen on one face of the sheet and the other on the other or opposite face, and there will be adjacent to each photograph a bordered space for receiving an autograph or any other suitable writing.

40 In Fig. 4 each sheet is shown with its two

photograph-pocket mouths, one autograph bordered space being behind one and the other in front of the other of the said photograph-pockets.

45 I am aware that autographic and photographic albums have been made with pockets for reception of the pictures, and also with pockets for reception of autographs, such being as represented in the United States Patents Nos. 67,540 and 169,186, and therefore I do not claim such as within my invention. I have no pockets for reception of the autographs written on separate strips of paper and inserted therein; but I have for the autograph a bordered 50 space on each side of the sheet, and alongside of the picture-pocket of that side. In the Patent No. 67,540 the pockets are arranged in each sheet, so as to bring the pictures "back to back," a separate piece of paper having slits in 55 it being pasted on the sheet, all of which differs from my invention, in which each leaf does not have its picture-pockets arranged so as to bring the pictures back to back.

60 I claim—

65 As a new article of manufacture, a photograph and autograph album constructed substantially as described—viz., with each leaf having to each of its sides not only an open pocket for reception and exhibition of a photograph, 70 but a bordered space for reception of an autograph or other writing, the pockets opening at one edge of and on opposite sides of the leaf, and so arranged with the autograph-receiving spaces or portions of the leaf that one of such 75 bordered spaces or portions and a pocket-opening for the display of a picture shall be on each side of the leaf, all being essentially as specified.

GEORGE BARTLETT.
